UNITED STATES PATENT OFFICE.

FRANK NAGY, OF NEW YORK, N. Y.

FIRE SCREEN OR GUARD.

1,127,493.

Specification of Letters Patent.

Patented Feb. 9, 1915.

Application filed May 2, 1914. Serial No. 835,827.

To all whom it may concern:

Be it known that I, FRANK NAGY, a citizen of the United States, residing at New York, in the county of Bronx and State of New York, have invented certain new and useful Improvements in Fire Screens or Guards; and I do hereby declare the following to be a full, clear, and exact description of the invention, such as will enable others skilled in the art to which it appertains to make and use the same.

This invention relates to fire screens or guards and is more particularly designed to be placed in front of fire places for preventing the sparks from the fire from lighting upon the floor of the room, and has for one of its objects the provision of a fire screen which may be readily folded together when not in use, thus occupying limited storage space.

A further object of this invention resides in the provision of a fire screen provided with means for conveniently conveying the same from one point to another when in folded position.

A still further object of this invention resides in the provision of a fire screen which is composed of indestructible material, simple in construction, ornamental in design, efficient and durable in purpose and which may be manufactured and sold at a nominal cost.

These and other objects will more fully appear and the nature of the invention more clearly understood by the construction, combination and arrangements of the parts thereof as described in the following specification, defined in the appended claim and illustrated in the accompanying drawings, in which,

Figure 1, is a view of the fire screen showing the same in complete set up position. Fig. 2, is a fragmentary view, partly in section, showing the manner of mounting the wire mesh within the frame of the screen sections, and the means for hingedly connecting the respective sections together. Fig. 3, is a longitudinal sectional view on line 3—3 of Fig. 2, showing the manner of securing the wire mesh within the screen frame. Fig. 4, is a detailed view, partly broken away, showing the manner of positioning the rods of the screen frame within the wire mesh.

Referring to the drawings, the fire screen is composed of several screen frames in

which 1 denotes the end frames and 2 the intermediate frames, there being four frames shown in the drawings, but it is to be understood that a greater or less number of screen frames may be used to meet the needs of the case. The screen frames are hingedly connected together at the bottom and top ends at the adjacent meeting side edges by the links 3, the top portions of the end frames 1 being provided with the handles 4 for conveniently carrying the fire screen from point to point when in folded or collapsed position.

Each of the screen frames is formed with the upper and lower horizontal wires or rods 5, and the vertical rods 6, and at the juncture or meeting points of the rods 5 and 6 is provided the angle sleeve 7, in one of the angular portions of which is seated the horizontal rod 5 and through the remaining portion of the angle sleeve 7, passes the vertical rod 6, the rods 5 and 6 within the angle sleeve 7, being secured therein to form a fixed connection by brazing or soldering the respective rods and the angle sleeve together.

It is to be understood that previously to the assembling of the rods 5 and 6 of the frames, that the horizontal rods 5 are passed through the meshes of the wire fabric 8 at the top and bottom edges thereof as shown at *a* in Figs. 2 and 4 of the drawings, while the vertical side rods 6 are passed through the meshes of the fabric 8 in a transverse direction. It is to be noted, however, by referring to Fig. 4, that the right hand rod 6 is passed through the meshes of the fabric 8 in a manner so that the wrapped portions of the mesh indicated at *c*, and *e* are positioned at the right of the rod, the left hand rod 6 being passed through the mesh in a manner whereby the wrapped portions of the mesh as indicated at *b* and *d* will lie at the left of the rod, and in this way it will be observed that the opposing side rods 6 engage the wrapped portions of the fabric 8 at alternate points along the transverse direction of the fabric, whereby when the rods 6 are forced outwardly from each other with the horizontal rods 5 interposed therebetween, the wire fabric 8 will be drawn under tension, thus causing the meshes to assume approximately a diamond shape.

Surrounding the rods 5 are the tubes or cylinders 9, the cylinders 9 being open seamed or slotted for their entire length as

shown at 10, the rods 6 being also provided with the cylinders 11 provided with the open seam or longitudinal slot 12, the slots 10 and 12 of the cylinders 9 and 11 respectively 5 being provided for the passage of the wire fabric 8 therethrough. The tubes or cylinders 9 and 11 are of a greater diameter than the rods 5 and 6, each of the cylinders 9 and 11 having their respective meeting 10 ends beveled as shown at 14, the space between the inner walls of the cylinders 9 and 11 and the rods 5 and 6 being filled with cement or other suitable light filling plastic substance as indicated at 15.

15 For hingedly connecting the respective screen frames together, the rods 6 project through the upper portions of the cylinders 9 for a distance above the same as shown at 16, and arranged upon the portion 16 of 20 the rods 6 are the washers 17, resting upon the upper surfaces of the cylinders 9, and for hingedly connecting the rods 6 of the adjacent screen frames are the links 3 having formed therein adjacent each of the 25 ends the apertures 19 for passing over the portion 16 of the rods 6 and resting upon the washers 17, and also positioned upon the portion 16 are the washers 20 and 21, the washer 20 resting upon the link 3 and the washer 21 being in spaced relation to the washer 20. The washers 17, 20, and 21 are 30 fixedly secured to the portion 16 of the rod 6 by clenching or other suitable means for fixedly securing the washers to the portion 35 16. The washers 20 and 21 are of less diameter however than the washer 17, and over the portion 16 of the rod 6 and surrounding the washers 20 and 21 but having its lower edge resting upon the links 3 are the caps 40 22, these caps being crimped at the point opposite the space between the washers 20 and 21 and forced inwardly at this point as shown at 23. This manner of mounting the links 3, the washers 17, 20 and 21 and the 45 caps 22 form efficient hinge connections between the respective screen frame sections, the links and washers being broad and flat prevents wobbling of the screen frame sections. The lower ends of the rod 6 also project slightly outwardly of the lower cylinders 9 and are provided with similar hinge connections as at the top portions thereof excepting the washers 21 and the caps 22 are omitted.

50 55 I desire to here state that in the construction of the fire screen or guard constituting

this invention, I have provided a light, ornamental, indestructible and cheap device. Among other features of this invention reside the link connections and the rigidity of the screen structure. By the use of the wire mesh 8, the rods 5 and 6 and the tubular cylinders 9 and 11 and by filling the space between the cylinders and the rods with cement or other suitable light plastic filling substance, I produce a screen which is extremely light and easy to handle and manipulate without detracting from the strength of the structure. A further feature of the invention resides in the efficient manner of hingedly connecting the respective screen frame sections at the top and bottom of the adjacent meeting side edges, for by the use of the broad washers, and the broad link connections are efficiently retained between the said washers which are fixedly secured to the projecting ends of the rods 6, thus forming a hinge connection for and preventing the wobbling of the screen frame sections of the fire screen structure. 70

While I have here shown and described the preferred form of my invention I hereby reserve the right to make such alterations and variations therein from time to time as I may deem expedient and which will not 85 depart from the spirit of this invention nor conflict with the scope of the claim.

Having thus fully described my invention, what I claim as new and desire to secure by Letters Patent is:— 90

A fire screen or guard, comprising a plurality of screen frames, horizontal top and bottom rods for said frames, vertical side rods for said frames, a woven wire fabric secured to said rods, the adjacent side rods projecting outwardly of said frames, links embracing the projecting ends of said adjacent side rods for hingedly connecting said frames together, caps for said adjacent side rods, slotted tubes surrounding said rods, said fabric passing through the slots of said tubes, said tubes being of a greater diameter than said rods and providing space therebetween, and a plastic filling in said tubes for embedding said rods therein. 100

In testimony whereof I have signed my name to this specification in the presence of two subscribing witnesses.

FRANK NAGY.
